UNITED STATES PATENT OFFICE

WILLIAM K. LIGGETT, OF COLUMBUS, OHIO, ASSIGNOR TO THE JEFFREY MANUFACTURING COMPANY, OF COLUMBUS, OHIO, A CORPORATION OF OHIO.

TRACTOR

Application filed April 26, 1924. Serial No. 709,253.

This invention has to do with improvements in tractors, and more particularly to the so-called "track layer" type, in which there is provided a plurality of endless chains, one at least on each side of the machine, which chains carry relatively broad ground-engaging treads, and are actuated from suitable power mechanism to move the machine.

10 The objects of the present invention are to provide an improved drive mechanism for actuating the endless chains, and, further, a control mechanism by means of which the machine may be steered and turned by proper manipulation of such control mechanism.

The means whereby I attain these objects are fully set forth in the following specification, and illustrated in the accompanying drawings, in which:—

20 Fig. 1 is a side elevation of the preferred embodiment of my invention.

Fig. 2 is an end elevation of the machine illustrated in Fig. 1.

Fig. 3 is a side elevation of the power jack, or self-contained power transmission devices 25 of the machine.

Fig. 4 is an end elevation of the power devices of the machine, other parts being omitted to simplify the figure.

30 Fig. 5 is a somewhat diagrammatic showing of the primary driving gearing which constitutes a part of the transmission mechanism.

Fig. 6 is a sectional view showing the end 35 of the gearing illustrated in Fig. 5, looking from the left, Fig. 5.

Fig. 7 is a somewhat diagrammatic showing of the reverse and equalizing gearing.

40 Fig. 8 is an end view of the gear illustrated in Fig. 7, looking from the left, Fig. 7.

Fig. 9 is a side elevation of the reversing gears, looking from the left, Fig. 8.

Fig. 10 is a perspective view of the tractor steering devices.

45 In the drawings, in which like numerals refer to similar parts in the several figures, I have shown an embodiment of my invention wherein the numeral 1 refers to the main frame upon which the operative parts of the machine are mounted. Attached to

the longitudinal sills 2 of the frame 1 is a power jack, or self-contained power transmission mechanism, by which power is transmitted from the motor 3 to propel the machine in a manner which will be hereinafter more fully set forth. The motor 3 is diagrammatically indicated in Figs. 1, 3 and 5, and may be of any convenient type suitable to the conditions under which the machine operates. The motor 3 is preferably supported directly upon the main frame of the machine, independent of the power jack, and is provided with a spur pinion 4 which meshes with the master gear 5 of the power jack.

The power jack comprises two parallel frames 6 and 7 which are held in spaced relation by suitable cross rods 8 and 9, and, as shown in Fig. 4, rest upon and are secured to the longitudinal sills 2 of the main frame. In the side frames 6 and 7 are formed suitable 70 journal bearings for the support of the several shafts included in the power transmission mechanism.

The master gear 5 is keyed to the shaft 10 which extends across the jack frame and projects at both sides thereof. On one projecting end of the shaft 10 is mounted a sprocket wheel 11 adapted to be connected through a suitable endless chain with any suitably positioned device which it may be desired to 80 actuate from the motor 3. The sprocket wheel 11 may be operatively connected to the shaft by means of a multiple disc friction clutch 12 (see Figs. 4 and 5) having a controlling lever 13 convenient to the hand of 85 the operator, by manipulation of which power may be applied to the sprocket wheel 11 for the purpose above described. As clutches of this type are well understood in the art, it is thought that the clutch 12 need not be 90 further described at this time.

Formed on the hub of the master gear 5 is the driving element 14 of a multiple disc friction clutch having a plurality of friction discs 15 arranged to connect said driving member with the driven member 16 when said discs are pressed together. The driven member 16 is secured to a sleeve 17 which is journaled upon the shaft 10, and a journal bearing 18, carried by an arm 18' mounted 100

on the tie rod 8, so as to be upheld by the jack frame, engages the periphery of said sleeve for the limitation of its endwise movement. Keyed to the shaft 10 at or near its opposite end is a spur pinion 19 which engages a back gear 20 freely rotatable upon the tie rod 8. To the hub of this back gear 20 is fixed a pinion 21 which engages a gear 22 rotatably mounted on the shaft 10. The hub 23 of the gear 22 constitutes one member of a multiple disc friction clutch which is connectable by a plurality of friction discs 24 with the companion clutch member 25 fixed to the sleeve 17. Formed in the side frame 6 of the power jack, is a bearing 26 in which is formed a relatively high pitch screw thread fitting with a similar thread formed on the periphery of a bearing sleeve 27. The upper journal block of the bearing 26 has the projection 26' in the form of a web extending upwardly therefrom, and from the upper end of this projection 26' tie rods 27' extend downwardly to the bearing 18 and the arm 18', so as to tie the frame parts together and give rigidity to the frame and bearings. The shaft 10 is supported in the sleeve 27, and thrust collars 28 and 29 attached to the said shaft prevent relative longitudinal movement of said shaft and sleeve. A hand lever 30, attached to the sleeve 27, affords means for its rotation in the bearings 26, and by said rotation, said sleeve 27, together with the shaft 10, may be moved longitudinally relative to the jack frame.

35 When the lever 30 is rotated in one direction, the shaft 10 will be moved towards the right hand side of the machine, causing the flange 31 of the clutch member 23 to press the discs 24 together, and thereby operatively connect the sleeve 17 with the shaft 10 to drive said sleeve 17 through the back gears 19, 20, 21 and 22, at a relatively low speed. When the lever 30 is rotated in the opposite direction, the shaft 10 will be longitudinally moved towards the left hand side (Fig. 5) of the machine to exert pressure upon the discs 15, and thereby connect the sleeve 17 directly with the gear 5 to cause revolution of said sleeve at the relatively high speed of the master gear.

Formed on the sleeve 17 is a spur pinion 32 which engages with a spur pinion 33 journaled upon a stationary shaft 34 carried by the jack frame. The pinion 33 meshes with the spur gear 35 which is freely mounted on the shaft 36, and it also meshes with a pinion 37 formed integral with the sleeve 38 which is journaled upon the stationary shaft 39. Formed on the sleeve 38 is a second spur pinion 40 which meshes with a gear 41, similar to the gear 35, and also freely mounted upon the shaft 36. A double faced jaw clutch 42 positioned between the gears 35 and 41, and splined to the sleeve 43, is adapted to engage suitable clutch teeth formed on the

sides of the gears 35 and 41, to connect either of said gears to the sleeve 43. A shifting lever 44 is arranged to control the clutch 42, and is provided with a handle 45 projecting through the sides of the housing 46 of the machine in position convenient to the hand of the operator, who, by manipulation of said handle and clutch, may throw either of gears 35 and 41 into action and cause the rotation of said sleeve 43 in either direction as preferred.

Fixed to the sleeve 43 is a pinion 47 which meshes with ring gear 48 of a differential driving gear of the well known bevel gear planetary type. This differential gear is provided with a plurality of bevel pinions 49, each of which engages both of the bevel gears 50 and 51 in the manner which is well understood in the art.

One of the bevel gears 50 is keyed to the shaft 52 which is suitably journaled in bearings in the main frame of the machine. The other bevel gear 51 is fixed to the sleeve 53 mounted concentrically with the shaft 52, and extending through the bearing 54 of the main frame. Fixed to the projecting ends of the shaft 52 and sleeve 53 are the hubs 55 and 56, to which are fixed the sprocket wheels 57 and 58. The sprocket wheels 57 and 58 are connected through the endless chains 59 and 60 with the sprocket wheels 61 and 62, fixed to the main traction sprocket wheels 63 and 64. The traction sprocket wheels 63 and 64 are freely journaled upon the axles 65 which are rigidly secured to the frame of the machine, and tractor chains 66 and 67 engage the said traction sprocket wheels and are actuated thereby to propel the machine. The traction chains 66 and 67 are of the usual and well known type having treads 68 suitable to engage the ground and to support the weight of the machine thereon. These tractor chains 66 and 67 pass around suitable sprocket wheels, guide rollers, and the like, to support the machine in the manner which is well understood in the art. Since the details of these devices form no part in the present invention, and are well understood in the art, further description is not thought to be required at this time.

Mounted upon the hubs 55 and 56 are the brake drums 69 and 70 which are engaged respectively by the brake bands 71 and 72. These brake bands 71 and 72 are connected through suitable toggle levers 73 and 74 with the brake lever 75 in such manner that when said brake lever is moved in one direction, one of these bands will be tightened upon its drum and the other released, and when said lever is moved in the opposite direction, the first mentioned band will be loosened and the other tightened. By the manipulation of the lever 75 the operator may optionally tighten either of the brake bands 71 or 72 to thereby retard or prevent the rotation of the respec-

tive brake drums. Through the action of the differential driving gear, when one of the brake drums is held against rotation, the other will be caused to revolve at a proportionally higher speed, and the rotary motion transmitted through the driving chains 59 and 60 will cause corresponding differential movement of the tractor chains 66 and 67 to turn the machine in the desired direction.

10 By the mechanism above described, my improved tractor may be propelled either forwardly or rearwardly at a relatively high speed, or at a relatively low speed, and it may be turned in any preferred direction 15 at the will of the operator.

A platform 76 mounted upon the main frame 1 at one side of the machine forms a convenient perch upon which the operator may ride, and all of the controlling levers 20 project through the housing 45 of the machine at points convenient to the hand of the operator when riding upon said platform.

It is obvious that changes in construction may be made and mechanical expedients 25 other than and equivalent of those here shown may be adopted, and I do not, therefore, limit myself to the detailed disclosures, except in so far as I am limited by the appended claims.

20 I claim:—

In a machine of the class described, a motor, an axially displaceable shaft driven by the motor, a drive element loosely mounted on said shaft, a driven member of a clutch 35 secured to said drive element at each side thereof, means for preventing displacement of said drive element and said driven members longitudinally of said shaft, respective driving members of the clutches disposed on said shaft in proximity to the driven members, connections for driving said driving members from said shaft in the same direction, each at a different speed, and means 40 for simultaneously displacing the driving members relative to the driven members of the clutches to selectively engage the clutches.

In testimony whereof I have hereunto set my hand.

WILLIAM K. LIGGETT.
